UNITED STATES PATENT OFFICE

EDGAR S. BOTT AND ARTHUR S. FUNK, OF LA CROSSE, WISCONSIN, ASSIGNEES TO LA CROSSE RUBBER MILLS CO., OF LA CROSSE, WISCONSIN, A CORPORATION OF WISCONSIN

UPPER AND PROCESS OF CONSTRUCTING SAME

Application filed April 19, 1928. Serial No. 271,321.

The invention relates primarily to a galosh having a turn-down cuff, and a pocket which increases the size of the upper when opened, for ease in applying and removing the galosh.

It is one aim of the invention to provide a new and improved construction in which the pocket is embodied in overlapped portions of the upper at one side of the latter and in which the ends of the cuff overlap each other at said side of the upper, providing not only a warm and weather-tight upper, but one which will possess an unusually attractive appearance.

15 A further aim is to provide an upper having a side pocket, and of such construction that the cuff when turned down, cannot overlap the pocket and produce an unsightly bulge, but may lie closely against the upper 20 to give a trim and attractive appearance, quite uncommon with galoshes.

A further aim is to provide for rapid and economical manufacture, and in this connection to make unique provision for the 25 production of a properly lined article.

With the foregoing in view, the invention resides in the novel subject matter herein-after described and claimed, description being accomplished by reference to the accompanying drawings.

Fig. 1 is a perspective view of the main upper-forming blank and a number of other parts, including the pocket lining and fastening straps, in juxtaposition.

35 Fig. 2 is a perspective view similar to Fig. 1, showing the pocket lining and the cuff in readiness for application, and showing the straps and their attaching means placed upon the main upper-forming blank.

40 Fig. 3 is a perspective view similar to Fig. 2 but showing the cuff and pocket lining applied to the blank.

Fig. 4 is a perspective view of the blank and parts connected therewith, shaped into upper 45 form.

Fig. 5 is a perspective view of the lining applied to the last.

Fig. 6 is a perspective view showing the assembled upper applied to the last around 50 the lining.

Fig. 7 is a perspective view illustrating the manner in which the lining is cut within the pocket after all parts have been vulcanized or otherwise securely fastened together.

Fig. 8 is a perspective view of the completed shoe with the cuff thereof turned down and lying above the pocket.

Both the construction and the process herein disclosed, will be rather specifically described, with the understanding however, that within the scope of the invention as claimed, variations may be made.

The numeral 8 denotes a blank preferably formed of fabric, said blank embodying a relatively short reach 9 and a comparatively long reach 10 at substantially right angles to each other. The reach 9 possesses a longitudinal outer edge denoted by the characters E and F and the associated arrows and lines, and a concave outer end denoted by the letters G and H, the portion G of this outer end, being at an acute angle to the portion F of the longitudinal edge, providing a substantially triangular surplus of material 11, from which a side pocket is to be formed. The reach 10 embodies a longitudinal outer edge denoted at A—B—C and an outer end J—K which is substantially straight and at an acute angle to the longitudinal edge portion A. The inner longitudinal edges of the reaches 9—10 are denoted at I, and the corner portion of these reaches connecting the outer longitudinal edges thereof is given the character D.

Slits 12 are formed in the reach 9 near the end portion H thereof, straps 13 have their inner ends passed through these slits, a strip of green rubber 14 is then applied over slits and strap ends, and a friction stay reinforcement 15 is applied over the rubber.

A cuff 17 is formed from outside fabric 18, inside fabric 19 and a layer of rubberized material or friction between them. This cuff is temporarily attached to the blank 8 along its edge I, for instance through the tackiness of a projecting edge of the friction 20 and the tackiness of a coating of green rubber or the like applied to the inner side of said blank, and this tackiness will serve

100

also to hold the parts 14—15—16 in place upon said blank.

A pocket lining 16 of suitable material is applied over the reinforcement 15. This lining 16 is of a size to extend entirely over the pocket-forming area 11, to extend from this area entirely to the edge I and to extend inwardly from the edge G—H a distance suitable to the purpose of lining a portion 10 of the shoe vamp, as will hereinafter appear.

The blank completed to the extent shown in Fig. 3 is folded substantially upon the line 21 and the portions of said blank at opposite sides of this line, form the tip and the vamp 15 of the shoe. The end portion K of the reach 10 is temporarily stuck to the longitudinal edge portion F of the reach 9, leaving the end portion J of said reach 10, projecting beyond said longitudinal edge portion F as 20 seen in Fig. 4, to form a front edge of one side quarter of the upper. The end portion H of the reach 9 forms a free rear edge for the upper part of the vamp, which portion is adapted to rearwardly overlap the front edge 25 J of the above-named side quarter. The end portion G of the reach 9 forms the upper end of a pocket P. The edge portions A—B—C—D—E form the lower edge of the upper, and the edge portion I constitutes the upper end 30 thereof, which end is provided with the cuff 17. It will be observed that this cuff extends entirely from the rear edge H of the vamp, to the front edge J of the above-named side quarter, so that when these upper portions 35 of the vamp and side quarter are overlapped, the ends of the cuff 17 are similarly overlapped, to produce a warm and weather-tight construction.

At a suitable time, an appropriate lining 40 22 is applied over an appropriate last 23 and has its lower edges suitably secured to an insole (not shown). This lining extends continuously around the last and preferably only 45 has one seam 24, located at the rear or other suitable location, but not at the side portion which is to be occupied by the pocket P.

The blank 8, either after shaping as seen in Fig. 4, or incident to such shaping, is placed around the last 23 and the lining 22 thereon. By means of a rubber coating, cement, etc., all internal parts of the upper, with the exception of the pocket P (already 55 equipped with the lining 16) and the cuff 17, are stuck to the lining 22. The pocket P is now folded rearwardly and by means of appropriate wrapping or in any other desired manner, the parts are held in assembled relation upon the last. Vulcanizing is now 60 accomplished and incident thereto the usual outer sole and foxing are secured in place. After vulcanizing, by separating the overlapped portions of the vamp and adjacent side quarter, the pocket P is opened as shown in Fig. 7 and the lining 22 is accessible. 65 Then, by means of an appropriate knife 25,

this lining is vertically slit from its upper end entirely to the bottom of the pocket P, the slit being indicated at 26 in Fig. 7. The portion of the lining 22 at one side of this slit has been firmly vulcanized to the upper portions upon which it lies, and the portion of said lining at the other side of said slit has been vulcanized upon the lining 16 which not only lines the pocket P, but the superposed part of the vamp.

After taking the vulcanized upper from the last, its edges are trimmed wherever advisable and an appropriate binding 27 is applied to them, or these edges may be finished in any other desired manner. Also, suitable 70 fastening means 28 are attached for co-action with the straps 13. These fastening means serve to hold the rear edge portion H of the vamp lapped upon the front edge portion J of the side quarter and hold the pocket P folded rearwardly upon said side quarter. The rearward folding of this pocket occurs substantially along the shade lines 29 of Fig. 7, and as this fold line is spaced a considerable distance from the rear edge H of the vamp, it will be seen that there is an extended overlap of this vamp, over the side quarter, giving warmth and weather protection.

As will be clear from Fig. 8, the width of the cuff portion above the pocket P is less than the distance from the top of said pocket P to the fold line 30 of said cuff. Thus, when this pocket P is downwardly turned as seen in this view, its overlapped ends will not overlap the pocket and cause a clumsy and unsightly bulge, but may lie snugly against the upper, giving an unusually trim and pleasing appearance. The overlapped pocket at the lower portion of the shoe is of substantially the same thickness as the overlapped and downturned end portions of the cuff, so that an unusually uniform appearance is given to the side of the shoe at which these formations are located. Moreover, by 100 employing the construction disclosed, the upper when in use, with the cuff 17 turned down, has no visible seam whatever, the seam which connects the edge portions F and K, being entirely hidden by the rearwardly 105 folded pocket P.

The process of manufacture herein disclosed has proven to be rapid and economical, and the article produced by such process is meeting with great success upon the market. Hence, the characteristics of process and article herein described are preferably obtained in the ways described, attention being again directed however to the fact that within the scope of the invention as claimed, 110 variations may be made.

We claim:

1. In a galosh upper, a vamp entirely free from one side quarter at the upper portion of the latter, the other side quarter and the 115 120 125 130

vamp being continuous, the lower portion only of said vamp having a surplus of material joined to the lower portion of said one side quarter at the front edge of the latter to form a pocket, of less height than the side quarters and terminating below the upper ends thereof, said pocket being normally folded rearwardly into flat form and overlapping the outer side of said lower portion of said one side quarter, the part of the vamp above said pocket being normally disposed in overlapping relation with the upper portion of said one side quarter, means for holding the parts in their overlapped relation, and a turn-down cuff at the top of the upper extending from the free rear edge of said vamp to the front edge of said one side quarter, whereby the ends of said cuff are overlapped at one side of the upper; termination of said pocket below the upper end of said one side quarter serving to overcome excessive thickness at said end under the overlapped cuff ends.

2. In a galosh upper, a vamp entirely free from one side quarter at the upper portion of the latter, the other side quarter and the vamp being continuous, the lower portion only of said vamp having a surplus of material joined to the lower portion of said one side quarter at the front edge of the latter to form a pocket, said pocket being normally folded rearwardly into flat form and overlapping the outer side of said lower portion of said one side quarter, the part of the vamp above said pocket being normally disposed in overlapping relation with the upper portion of said one side quarter, means for holding the parts in their overlapped relation, and a turn-down cuff at the top of the upper extending from the free rear edge of said vamp to the front edge of said one side quarter, whereby the ends of said cuff are overlapped, the cuff portion above said pocket being of no greater height than the distance from the upper end of said pocket to the upper end of said one side quarter, whereby upon downward folding of said cuff the overlapped ends thereof will not overlap the pocket but will lie closely against the upper.

3. In a process of forming an upper having a side pocket, the steps of forming a blank having a relatively short reach provided with a concave end, and a comparatively long reach at an angle to said short reach and having a substantially straight end; the outer longitudinal edge of said short reach and said concave end thereof being at an acute angle to each other; folding the blank substantially along the line of juncture between said reaches; securing the part of said outer longitudinal edge of the short reach toward said concave end, to the part of the relatively long reach end toward the outer longitudinal edge of said long reach, leaving the remainder of the last named end projecting beyond said

outer longitudinal edge of said short reach to form a free front edge of a side quarter, the material within the aforesaid acute angle then forming a foldable pocket whose upper edge is formed by part of said concave end of said short reach, the remainder of said concave end constituting a free rear edge for the vamp of the upper.

4. In a process of forming a lined upper having a pocket, the steps of applying a continuous lining to a last, forming an upper-forming blank with a pocket-forming surplus of material, securing all parts of said blank except said pocket-forming surplus against said lining and leaving said surplus protruding to form a pocket, and vertically slitting the lining within said pocket.

5. In a process of forming a lined upper having a pocket, the steps of applying a continuous lining to a last, forming an upper-forming blank with a pocket-forming surplus of material, applying a pocket lining to said pocket-forming surplus, securing all parts of said blank except the lined pocket-forming surplus thereof against said lining and leaving said surplus protruding to form a pocket, and vertically slitting the lining within said pocket.

In testimony whereof we have hereunto affixed our signatures.

EDGAR S. BOTT.
ARTHUR S. FUNK.
